UNITED STATES PATENT OFFICE.

JOSEPH HESSE, OF HARTINGTON, NEBRASKA.

SEED-CORN DRIER.

1,258,217.

Specification of Letters Patent. Patented Mar. 5, 1918.

Application filed July 30, 1917. Serial No. 183,571.

To all whom it may concern:

Be it known that I, JOSEPH HESSE, a citizen of the United States, residing at Hartington, in the county of Cedar and

5 State of Nebraska, have invented certain new and useful Improvements in Seed-Corn Driers, of which the following is a specification, reference being had to the accompanying drawings.

10 This invention relates to devices for drying seed corn, and particularly to devices in which the seed corn is supported so as to secure a free circulation of air around the ears of corn.

15 One object of my invention is to provide a device of this kind which may be very cheaply made and cheaply sold, and which will support a maximum number of ears of corn.

20 A further object is to provide a device of this character comprising a sheet metal plate operatively supported and having cob engaging spurs struck out from the plate and projecting in opposite directions, so that 25 ears of corn may be disposed on opposite sides of the plate.

A further object is to so arrange these spurs that a maximum number of spurs may be disposed upon the plate, without weakening 30 the plate.

A further object is to provide a construction of this character in which free circulation of air is secured through the plate as well as around the ears of corn.

35 A further object is to so form the plate to provide the spurs, that the spurs will be so spaced as to take up all available space on both sides of the plate while not materially weakening the sheet or plate.

40 Other objects will appear in the course of the following description.

My invention is illustrated in the accompanying drawings, wherein:—

Figure 1 is a front elevation of my improved seed corn support; and

Fig. 2 is a top plan view of the construction shown in Fig. 1.

Referring to these drawings, 10 designates a plate of sheet metal of any suitable size 50 or gage. This plate is reinforced at its side edges by means of vertical bars 11, which are riveted to the plate and extend downward and are downwardly and outwardly curved as at 12 so as to form legs supporting the plate. These legs 12 extend in the same 55 direction. The middle of the plate is rein-

forced by means of a vertically extending bar 13, which is riveted to the plate and extends downward and is outwardly curved but in an opposite direction to the legs 12. 60

The plate 10 is provided with a plurality of spurs 14 which project out on opposite sides of the plate and in opposite directions. These spurs are formed by cutting the plate with a plurality of V-shaped cuts, the cuts 65 being designated *a*, and then bending the V-shaped tongue or spur thus formed outward and away from the plate. These cuts *a* are arranged in transverse rows extending across the plate any desired distance from each other and the alternate cuts are reversed with relation to the adjacent cuts. Thus in one set of cuts the apex of the V extends downward and in the other set of cuts, the apex of the V extends upward. 70 Furthermore, the base of any one triangular or V-shaped cut is disposed in staggered relation to the base of the next adjacent V-shaped or triangular cut in the same transverse row as illustrated clearly in Fig. 1. 75

After the plate has been formed with these V-shaped cuts, the prongs or spurs 14 are bent outward, and the spurs, which prior to being bent outward have their points extended upward, are bent down and out to 80 a plane at right angles to the plane of the plate, while the spurs which prior to being bent outward have their points extend downward, are bent upward into a plane approximately at right angles to the plane of 85 the plate. Preferably all of the spurs will be bent to a position inclined slightly upward and outward.

It will be noted that by arranging the spurs in the manner described that the plate 90 may be formed with a great number of spurs, without substantially weakening the plate, as the imperforate webs between the openings left by bending out the spurs will be strong enough to keep the plate from 100 bending. Furthermore, the end and middle bars which form the legs brace this plate and hold it firmly. Preferably the legs and the bars 11 will be formed at their upper ends with hooks 15 whereby this sheet metal 105 rack may be suspended from the rafters of a barn, so that the device may either stand up on its own legs or be suspended as desired. It will be seen that by alternating the direction of the cuts, as illustrated, the 110 metallic sheet will not be weakened, as it would be if the bases of all the cuts were

disposed in approximately the same plane and the V-shaped cuts extended in the same direction. In this case the V-shaped cuts would have to be put farther apart than 5 they do with my improved construction, so as to leave sufficient space between the bases of the triangular cuts.

It will be obvious that the device may be made in different forms and may be modified 10 in many details, without departing from the spirit of the invention. It will also be seen that the ears of corn are supported in spaced relation to each other, so that there is a free circulation of air around the ears, 15 and further that the openings formed by striking out the several spurs or prongs permits the air to circulate freely through the plate itself and around the ears of corn.

Having described my invention, what I 20 claim is:-

1. A seed corn drier including a metallic sheet having a plurality of rows of V-shaped cuts in the sheet, the material defined by said cuts being bent outward in opposite directions so as to provide a plurality of cob engaging prongs projecting from opposite faces of the sheet, the cuts in each row being alternately directed upward and downward.

2. A seed corn drier including a metallic 30 sheet having a plurality of rows of V-shaped cuts in the sheet, the material defined by said cuts being bent outward in opposite directions so as to provide a plurality of cob engaging prongs projecting from opposite 35 faces of the sheet, the cuts in each row being alternately directed upward and downward, the bases of alternate cuts in each row being disposed in staggered relation to the adjacent cuts.

Copies of this patent may be obtained for five cents each, by addressing the "Commissioner of Patents, Washington, D. C."

3. A seed corn drier including a sheet of metal formed with a plurality of vertically extending rows of V-shaped cuts, the cuts in certain rows being disposed with their apices downward, the cuts in the next adjacent rows being disposed with their apices 45 upward, the prongs defined by said first named cuts being bent outward in one direction and the prongs defined by the second named cuts being bent outward in the opposite direction.

4. A seed corn drier including a sheet of metal formed with a plurality of vertically extending rows of V-shaped cuts, the cuts in certain rows being disposed with their apices downward, the cuts in the next adjacent rows being disposed with their apices 55 upward, the prongs defined by said first named cuts being bent outward in one direction and the prongs defined by the second named cuts being bent outward in the opposite direction, the bases of the cuts in one row being in staggered relation to the bases of the cuts in the next adjacent rows.

5. A seed corn drier including a metallic sheet having prongs struck out of the sheet and projecting in opposite directions, the prongs being arranged in vertical and transverse rows, and reinforcing bars riveted to the sheet and extending vertically across it and formed at their lower ends to provide 60 legs extending in opposite directions.

In testimony whereof I hereunto affix my signature in the presence of two witnesses.

JOSEPH HESSE.
